METHOD OF AND MEANS FOR PROPELLING SHIPS

Application filed June 5, 1928. Serial No. 282,920.

This invention relates in general to a method of and means for propelling ships. It is a recognized fact that the greatest resistance to be overcome in propelling high speed ships, is the water at the point where the ship takes entrance, that is at the bow; in other words a large amount of power is necessary to displace or push aside the water so that the ship may move, which produces what is known as the bow wave. Ordinarily this power is now provided by the thrust of the propeller at the stern of the ship, and the indicated power in the engine room required for the purpose is approximately twice that actually exerted at the bow, the difference being lost in the prime mover or engine, its electrical or mechanical transmission gearing and in the propellers.

One object of my invention is to provide a novel and improved method and means for displacing the water at the ship's bow and thereby reduce or eliminate the resistance now caused by the bow wave.

Another object is to cause such displacement of water at the bow by exerting an auxiliary or extraneous force on the water in advance of the bow to force the water downwardly and laterally away from the ship.

A further object is to provide a novel and improved method and means for exerting force on the water adjacent the exit surfaces of the ship to create pressure waves or a hydrostatic head which acting upon said exit surfaces will push the ship forwardly.

Other objects are to provide such a method and means wherein an explosive charge is utilized to displace the water, said charge being exploded between a certain special portion of the ship's hull and the water to be displaced; to provide novel and improved means on a ship's hull to form conjointly with the water an explosion chamber for the explosive charge, and to obtain other advantages and results as will be more fully brought out by the following description.

In the accompanying drawings I have schematically illustrated one manner and means for carrying out my invention but I do not desire to be understood as limiting myself to the specific details shown.

Referring to said drawings in which corresponding and like parts are designated throughout the several views by the same reference characters,

Figure 1 is a plan view of the hull of a ship embodying my invention,

Figure 2 is a side elevation of the ship viewing the same from the line 2-2 of Figure 1.

Figures 3, 4, 5, 6, 7, 8, 9, 10, 11, 12, and 13 are transverse vertical sectional views taken on the respective lines 3-3, 4-4, 5-5, 6-6, 7-7, 8-8, 9-9, 10-10, 11-11, 12-12 and 13-13 of Figure 1.

Figure 14 is a vertical longitudinal sectional view taken on the line 14-14 of Figure 1.

Figure 15 is a similar view taken on the line 15-15 of Figure 1.

Figure 16 is an enlarged fragmentary vertical longitudinal sectional view taken on the line 15-15 of Figure 1.

Figure 17 is an enlarged fragmentary horizontal sectional view taken on the line 17-17 of Figure 15.

Figure 18 is an enlarged fragmentary transverse vertical sectional view taken on the line 18-18 of Figure 16, and

Figure 19 is a view similar to Figure 2 showing a modified form of the invention.

Specifically describing the illustrated embodiment of the invention, the reference character A designates the hull of the ship which includes the deck B, sides C and bottom D. The hull has a pointed bow 1 with a flat horizontal bottom 2 which extends a short distance below the normal water level E, for example six feet. The rear end of said flat bottom 2 of the bow merges at 3 into a downwardly and rearwardly inclined portion 4

which extends to the full depth of the ship and merges at 5 into the main bottom 6. The portion 4 thus simulates the bow portion of the known socalled sea-sled type of boat. A longitudinal median fin 7 depends from the horizontal bottom 2 of the bow portion 1, the forward end of said fin being in substantially juxtaposition to the juncture points of the pointed sides of the bow with the sides C of the hull. This fin extends rearwardly and gradually merges into the inclined portion 4 and the main bottom 6 of the hull.

Secured to the underside of the horizontal bottom 2 of the bow portion 1 are a plurality of projections or vanes 70 which are substantially parallel with each other and extend longitudinally of the hull parallel with its longitudinal median line. As shown, the forward ends of the vanes 70 are in transverse alignment with the forward end of the fin 7, but the rear ends of the vanes terminate short of the inclined entrance surfaces 4 as indicated at 71. The sides of the hull opposite the vanes 70 depend below the horizontal bottom 2 parallel with said vanes as indicated at 72, said sides extending downwardly into the water a somewhat greater distance than the vanes 70. In accordance with the invention explosive charges are supplied to and exploded in the spaces between adjacent vanes 70 and between the sides 72 and the fin 7 and the next adjacent vanes; and these spaces 8 thus serve in effect as explosion chambers, one side, i. e., the bottom, and both ends of which are closed by or constitute the water.

Any suitable means may be utilized for supplying the explosive charges to and explosion chambers 8, and any suitable explosive charge may be utilized. For the purpose of explaining the principles of my invention, however, I have schematically shown one such means which comprises an air compressor 10 driven by suitable motor 11 and supplying air through a pipe 12 and a rotary valve 13 to a plurality of pipes 14, 15, 16 and 17 which extend longitudinally forward through the bow portion 1 as indicated in Figures 16 and 17 of the drawings. The valve 13 may be of any suitable construction, for example, two discs revolving in opposite directions and having a plurality of openings adapted to successively register in different positions and successively distribute the air to the respective ducts or passages 14, 15, 16 and 17. These ducts lead forwardly and each one supplies air to corresponding chambers 8 at opposite sides of the fin 4, the ducts having the respective branch passages 18, 19, 20 and 21 which extend laterally through the bottom 2 and then forwardly to the forward ends of the respective chambers 8 (see Figures 16 and 17). The forward extremities of the branch ducts 18, 19, 20 and 21 each terminate above one of the explosion chambers 8 in a distributing ante-chamber

230 having outlets 22 controlled by outwardly opening poppet valves 23 or the like leading into the forward end of the respective explosion chamber. At the top of each chamber 8 is arranged a carburetor 25, which mixes gasoline, gas, oil or other suitable fuel with the air supplied through the outlets 22. The fuel may be supplied to the carburetor in any suitable manner.

The explosion mixture is exploded at approximately the longitudinal center of each chamber 8 by any suitable means, for example, a metal ring 26 arranged in the web 5 and having a portion thereof protruding into the corresponding chamber and thinner than the other portions of the ring, said ring having an electric current induced therein by a coil 27 wound upon a magnetic core 28. The thinned portion of the ring produces a high electrical resistance so that the current heats said ring to incandescence.

In operation of the invention, the air is supplied at the forward end of each of the explosion chambers 8 from the compressor 10 and through the ducts 14, 15, 16 and 17 and outlet openings 22, the poppet valves 23 opening under the air pressure. The air thus supplied is carbureted with fuel by the carburetor 25 and forms a small bubble as shown at 30 in Figure 14. Forward movement of the ship relative to said bubble brings the incandescent portion of the igniting ring 26 into contact with the explosive mixture in the bubble as shown in Figure 15, whereupon said mixture is exploded and expands as shown at 31 in Figure 5. This expansion forces the water downwardly and outwardly of the explosion chamber and consequently in a lateral direction to the sides of the hull, as indicated by arrows in Figures 5 and 6 of the drawings, which show the expansion of the explosion gases at two different stages. This causes a displacement of the water immediately preceding the entrance surface 4 of the ship so that a trough is formed in which said entrance surface takes entrance as shown at 42 in Figure 14. On the sides C of the hull the water is piled up due to the lateral displacement thereof, as indicated at 33 in Figures 2 and 5 to 8 inclusive, but as these sides are in a vertical plane this water produces no resistance to the forward travel of the hull except such as is due to skin friction. The water level 33 at the sides of the hull as it leaves the sides or entrance surfaces of the bow gradually rises and at the same time its velocity away from the bow approaches zero; in Figure 7 of the drawings the water level is shown at the point where the entrance of the ship has to a large extent been taken, while Figure 8 shows the water level at the point of complete entrance of the bow. At this point the static head of the water at the sides of the ship is at a maximum and the water has entirely lost its velocity away from the hull, 130

It will be observed that the bow portion 1 extends such a distance below the normal water level that the resistance by the bow wave on the entrance surfaces 100 of said bow portion will be relatively slight.

Preferably the explosive mixture is admitted to the various chambers 8 at different times, this being controlled by the valve 13. For example, at the moment a bubble is exploded in one chamber, a bubble in the next adjacent chamber may be nearing the limit of its expansion, while in the next adjacent chamber on the other side, a bubble of explosive mixture may be forming. It is of course necessary that the vanes 70 extend sufficiently deep to prevent the expanded explosion gases in one chamber from escape into adjacent chambers, but said explosion gases will escape at the rear ends of the vanes. The shallow bow portion 1 may serve to carry a part of the cargo which may reinforce the bow portion under the impacts of explosions.

Entrance of the hull may be taken in two stages instead of in one stage as above described. One manner of accomplishing this is illustrated in Figure 19 of the drawings where the ship is provided with two entrance surfaces 37 and 38 in spaced relation longitudinally of the hull and connected by a horizontal bottom portion 39 corresponding to the bottom portion 2. The longitudinal median fin 40 may be extended rearwardly from the horizontal bottom portion 2 to the horizontal bottom portion 39, and merges into the main bottom of the ship at the rear end of the second entrance surface. On the horizontal bottom portion 39 are provided a second series of vanes 41 substantially identical with the vanes 70 and air and fuel may be supplied to the explosion chambers between these vanes in the same manner as the explosive mixture is supplied to the explosion chambers 8 and preferably by connecting branch pipes to the pipes 14, 15, 16 and 17 corresponding to the branch ducts 18, 19, 20 and 21 above described. With this form of the invention the explosions in the explosion chambers 8 force the water downwardly and laterally away from the entrance surface 37 as before described, and explosions in the chambers between the vanes 41 force the water out of the path of the entrance surface 38. This form of the invention is particularly advantageous in rough seas, where it is possible that the forward explosion chambers 8 would be inoperative part of the time because of being raised out of the water by wave motion.

It may be desirable in some instances to impart energy to the water in advance of the stern or exit surfaces 43 of the hull so as to exert a propelling force on said exit surfaces. For this purpose the hull may be provided with two vertical walls 34 one at each

side of the hull in spaced relation thereto and supported from the hull in any suitable manner as by the horizontal webs 35. Below the normal level of the water and secured to the inner sides of said walls 34 are a plurality of downwardly inclined vanes 36 which with the respective wall 34 and the surrounding water form explosion chambers similar to the chambers 8. An explosive mixture is supplied to and exploded in said chambers in any suitable manner and the result of the explosion drives the water between the walls 34 and the sides of the hull toward the hull and upwardly and downwardly in the direction of the arrows in Figures 9 and 10, which raises the water level or produces a pressure wave in advance of the exit surfaces 43. The force thus exerted on the water is imparted to the exit surfaces 43 so that the hull is pushed forward by said pressure as the water tends to resume its normal level as shown in Figures 11 and 12.

It will be understood that the ship may be propelled by the usual mechanism such as the engine and screw propeller, or the propelling force may be wholly that produced by explosion of the mixture in the chambers formed by the vanes 36 and the side walls 34; in the latter case the displacement of the water at the bow of the ship and the raising of the level of the water at the stern of the ship providing a sufficient difference in hydrostatic pressure at the bow and stern to cause forward movement of the ship.

This application is related to my co-pending application, Serial No. 269,688, filed April 13, 1928, wherein claims for reducing the hydrostatic pressure at the bow of the ship are included.

Having thus described my invention, what I claim is:

1. The method of propelling ships consisting in displacing the water in advance of the entrance surfaces of a ship's hull by exploding an explosive mixture beneath the surface of the water so that expansion of the explosion gases sets the water in motion downwardly and laterally away from the entrance portions of the hull, and applying a propelling force to the hull.

2. The method of propelling ships consisting in displacing the water in advance of the entrance surfaces of a ship's hull by confining an explosive mixture below the surface of the water in advance of the bow of the ship against movement in all directions except downwardly, exploding said mixture so that the expansion of the explosion gases displaces the water downwardly and laterally away from the entrance surfaces of the ship, and applying a propelling force to the hull.

3. The method of propelling ships consisting in displacing the water in advance of the entrance surfaces of a ship's hull by exploding an explosive mixture beneath the sur-

face of the water so that expansion of the explosion gases sets the water in motion downwardly and laterally away from the entrance portions of the hull, and exploding an explosive mixture beneath the surface of the water in advance of the exit surfaces of the hull and directing the explosion gases downwardly and toward said exit surfaces to create a pressure wave and increase the normal hydrostatic pressure upon said exit surfaces which exerts a forwardly propelling influence on the hull.

4. The method of propelling ships consisting in reducing the normal hydrostatic pressure at the bow of the ship, and exploding an explosive mixture beneath the surface of the water in advance of the exit surfaces of the hull and directing the explosion gases downwardly and toward said exit surfaces to create a pressure wave and increase the normal hydrostatic pressure upon said exit surfaces which exerts a forwardly propelling influence on the hull.

5. A ship's hull having means at its bow ahead of the entrance surfaces for receiving and confining an explosive mixture beneath the surface of the water and against movement in any direction except downwardly, and means for exploding said mixture so that the expansion of explosion gases forces the water downwardly and outwardly away from said entrance surfaces.

6. A ship's hull having an explosion chamber at its bow ahead of the entrance surfaces closed at its bottom by the water, means for supplying an explosive mixture under pressure to said chamber, and means for igniting said explosive mixture so that the expansion of the explosion gases forces the water downwardly and outwardly away from said entrance surfaces.

7. A ship's hull having an elongated longitudinally extending explosion chamber at its bow ahead of the entrance surfaces and closed at its bottom by the water, means for supplying an explosive mixture under pressure to the forward end of said chamber, and means for igniting said explosive mixture arranged in said chamber intermediate its ends, so that a bubble of explosive mixture is formed at the forward end and said igniting means is moved forwardly upon movement of the ship into said bubble to explode said mixture and the explosion gases expand at the rear portion of said chamber to force the water downwardly and outwardly away from said entrance surfaces.

8. A ship's hull having a plurality of longitudinally extending explosion chambers at its bow ahead of the entrance surfaces of the hull and equally distributed upon opposite sides of the longitudinal median line of said hull, the water serving as the bottom walls of said chambers, means for supplying explosive mixture under pressure successively to said

chambers, means arranged intermediate the ends of each chamber for igniting the explosive mixture therein so that a bubble of explosive mixture is formed at the forward end and said igniting means is moved forwardly upon movement of the ship into said bubble to explode said mixture and the explosion gases expand at the rear portion of said chamber to force the water downwardly and outwardly away from said entrance surfaces.

9. A ship's hull having an elongated longitudinally extending explosion chamber at its bow ahead of the entrance surfaces and closed at its bottom and rear end by the water, means for supplying an explosive mixture under pressure to the forward end of said chamber, and means for igniting said explosive mixture arranged in said chamber intermediate its ends, so that a bubble of explosive mixture is formed at the forward end and said igniting means is moved forwardly upon movement of the ship into said bubble to explode said mixture and the explosion gases expand at the rear portion of said chamber to force the water downwardly and outwardly away from said entrance surfaces, said explosion gases escaping into the atmosphere at the rear end of said explosion chamber.

10. A ship's hull having a substantially vertical wall in spaced and parallel relation to each side thereof depending into the water in advance of the exit portions of the hull, and means for exploding an explosive mixture beneath the surface of the water between said walls and the sides of the hull to produce pressure waves and increase the normal hydrostatic pressure upon the exit portions of the hull.

11. A ship's hull having a plurality of explosion chambers in spaced relation to the sides of the hull beneath the surface of the water in advance of the exit portions of the hull, said chambers having their bottoms closed by the water, and means for exploding an explosive mixture in said chambers to create pressure waves and increase the normal hydrostatic pressure upon the exit portions of said hull.

12. A ship's hull having a substantially vertical wall in spaced and parallel relation to each side thereof depending into the water in advance of the exit portions of the hull, said walls each having a plurality of explosion chambers thereon beneath the surface of the water whose bottoms are closed by the water, and means for exploding an explosive mixture in said chambers to produce pressure waves and increase the normal hydrostatic pressure on the exit portions of the hull.

13. A ship's hull having entrance surfaces and a horizontal member extending forwardly from said entrance surfaces below the level of the water, a plurality of elongated explosion chambers on the underside of said member and extending parallel to the longitudinal

median line of the ship closed at both ends and bottoms by the water, said chambers being equally distributed at opposite sides of said median line, means for supplying an explosive mixture under pressure to the forward portions of said chambers, and means arranged intermediate the ends of each chamber for igniting said explosive mixture so that the explosion gases expand in the rear portions of said chambers and force the water downwardly and outwardly away from the entrance surfaces of the hull.
